LIFE SAVING EQUIPMENT

Application filed December 31, 1928. Serial No. 329,463.

This invention relates to life saving equipment for use on marine vessels and has particular reference to the construction of a life saving buoy within which a score or more persons may be carried and which may be quickly and easily launched and which cannot be tipped or tilted in any manner that would cause the casting out of any of its occupants during the launching operation.

10 It is the principal object of this invention to provide a life saving device in the form of a closed buoy, within which a score or more persons may be secured in a safe and comfortable manner, and to equip this buoy with means whereby, if such is necessary or desired, it may be launched by one of its occupants, or it can be launched by persons on the deck of the vessel on which it is carried.

20 It is a further object of this invention to so construct a launching davit for the buoy that the latter will automatically be swung clear of the deck of the vessel as soon as it is lifted clear of the blocks on which it is normally supported and its weight thereby transferred to the davit.

25 A further object is to provide the buoy with compartments in the bottom portion thereof for the storage of fresh water and food supplies which will serve as ballast for holding the buoy in an upright position.

30 A still further object of the invention is to make provision whereby the buoy, after being launched, may be propelled and steered by its occupants.

35 Other objects of the invention reside in the various details of construction and in the combination of parts and in their mode of operation, as will hereinafter be described.

40 In accomplishing these and other objects, I have provided the improved details of construction, the preferred forms of which are illustrated in the accompanying drawings, wherein—

45 Figure 1 is a vertical cross section of a life saving buoy constructed in accordance with the present invention.

Figure 2 is an elevation, illustrating the manner of mounting the buoy on the deck of a vessel and the manner in which it is suspended from the launching davit.

Figure 3 is an enlarged view of the launching davit and tackle mechanism associated therewith.

Referring more in detail to the drawings—

1 designates, in its entirety, a life saving buoy constructed in accordance with the present invention. This buoy consists of a circular vessel, preferably of sheet metal construction, provided centrally at the top with an opening 2 through which the occupants may enter and leave the device; this opening being equipped with an outwardly opening closure, or cover, 3 that is hingedly attached, as at 4, and which is adapted to be secured tightly in closed position by means of a bolt, 5, or other suitable device, as designated at 6, which is releasable from within the buoy. In the upper wall of the buoy, about the opening 2, there is a plurality of port holes 7 adapted to be closed tight by inwardly opening closures 8 of any suitable character and which preferably would include glass panels for the admittance of light. At one side of the opening 2 is a vertically adjustable stack, or ventilating tube, 9 for the admittance of air, or, which may serve for the extension therethrough of a periscope, or the like. A staff 10 is attached to this stack for the support of a flag or pennant.

The side walls 11 of the vessel are flared 80 slightly as they extend downwardly, so that the diameter of the buoy is a little greater at the base than at the top, thereby avoiding any top heaviness which might tend to cause tipping or tilting. The bottom wall 12 is 85 downwardly curved and spaced above this, is a floor 13 beneath which is formed a plurality of separate compartments 14 within which water and provisions may be stored and which will serve in the capacity of ballast to add sea worthiness and stability to the device.

Encircling the buoy within the side walls, are shelves 16 on which the occupants may sit, and at one side, there are vertical bars 17, 95 serving as supports for cross bars 18 forming a ladder by means of which occupants may enter or leave the device.

When the buoy is placed on the deck of a vessel, it rests on supporting blocks 20 and is 100

anchored in place by means of a plurality of guys 21 which have their lower ends secured to the deck, as shown in Figure 2, and have their other ends attached to bolts 22 which project through openings 23 in the side walls of the buoy and are secured there by removable keys 24 through their inner ends. The keys 24 are located within the buoy and are designed so that they may be readily removed by persons within the buoy. Removal of the keys releases the anchoring guys and frees the buoy for launching.

The device is adapted to be launched from a davit 25 which is mounted on the deck of the vessel, as shown in Figure 2, with its upper, horizontally extended end portion overlying the buoy and its lower end rotatably mounted in a supporting socket 26 which has a downwardly and laterally sloping top surface 27. A pin 28 fixed in the davit bears against the sloping surface of the socket and when the weight of the buoy is transferred to the davit the latter will rotate in the support 26 to swing the buoy to a position at the side of the vessel where it may be safely launched.

As here shown, the buoy has a suspending bail 30 attached to pins, or bolts, 31 which are projected through openings 32 at opposite sides of the entrance 2 and are secured therein by keys 33 through their inner ends. The bail is suspended from a hook 34 attached to a tackle block 35 and this block is suspended from a block 36 by means of the windings of a cable 37. The block 36 in turn is attached to a hook 38 at the outer end of the davit. In a preferred arrangement, the lower block is a triple sheave construction and the upper block is a double sheave construction.

The deck end of the cable 37 is wound on a reel 40 that is attached to the davit near its base end. From this the cable extends upwardly along the davit over suitable guides 41 and then downwardly from the end of the davit and is threaded through the blocks 35 and 36, as shown, then it leads upwardly and over a pulley 47 fixed on the davit, and then downwardly, through an opening 48 in the top wall of the buoy, and is wound about a drum 50 located within the buoy. The drum 50 is mounted on a revolvably supported shaft 51 and may be revolved therewith by means of a crank 52 on the shaft so as to wind the cable 37 onto or from the drum. A suitable crank 53 is also provided for rotating the drum 40 for launching the device from the deck of the vessel, as will presently be more fully described, and suitable retaining pawls 54 and ratchets, as at 54, are associated with the reels 40 and 50 to prevent unwinding except when desired.

For the purpose of manually propelling the device from within, I have provided the buoy with a propeller 55 mounted in the

outer end of a drive shaft 56 which extends through the buoy wall and is connected at its inner end through suitable gearing as at 57, a vertical shaft 58 and gearing 59, with the shaft 51 so that rotation of the latter, by means of the crank 52, will also turn the propeller. A suitable clutch device, as at 60, is also provided whereby the reel 50 may be disconnected from the propeller mechanism or the propeller drive disconnected from the reel. A rudder 61 is also provided, rearwardly of the propeller, and this is operated under the control of a lever 62 that extends within the buoy. A suitable guard, or frame, 63 is fixed to the buoy to protect the propeller and serves also as the support for the rudder.

While it has not been illustrated herein, it may be desirable to locate the propeller and rudder within a recess that could be formed upwardly within the bottom wall of the buoy instead of these parts being located in the manner shown, and when so located, they would be better protected from obstacles with which the device may come in contact. However, the location of these parts is more or less optional.

Assuming the device to be so constructed, it is to be used as follows: In cases of emergency, the occupants enter the device through the top opening 2 while the buoy rests on the deck of the vessel; then, when the buoy has been loaded, the guys 21 are detached by pulling the keys 24 and then the top opening 2 is closed by lowering the cover 3 and securing it in place by means of the bolt 5. If the buoy is to be launched by an occupant, this is done by rotating the shaft 51 by means of the crank 52, so as to wind in the cable 37 on the drum 50 sufficiently that the buoy will be lifted free of the supporting blocks 20. As soon as the weight of the buoy is thus transferred to the davit, the latter, by virtue of its rotatable mounting in the support 26 and the inclined top surface of the latter, will be caused to rotate and swing the buoy outwardly to the side of the vessel. The occupant then unwinds the cable 37 from the drum 50, thereby lowering the buoy into the water. If the launching is to be done by persons on the deck, this is done in a similar manner by first winding in the cable on the drum 40 to free the buoy of the supporting block 20; then, after the buoy has been swung to a position at the side of the vessel, the cable is unwound from the drum 40 and the buoy thereby lowered into the water. After the device has been lowered into the water, it is cast free of the supporting tackle by pulling the keys 33 which attaches the bail thereto.

In case of rough water, the port holes 6 would be left closed and ventilation would be afforded through the stack 8. If the water is calm, the port holes and the top opening 2 may be left open.

After the buoy has been lowered into the

water and the winding drum 50 freed from the shaft 51, the crank 52 is rotated so as to revolve the propeller for moving the device and steering is done by manipulation of the rudder controlled lever 62.

Such devices may be made in various sizes and in various shapes, and it is readily apparent that certain details of construction may be varied without departing from the spirit of the invention. Therefore, it is not desired that the claims be limited only to the details that are herein shown.

Having thus described my invention, what I claim as new therein and desire to secure by Letters-Patent, is:

1. A life saving equipment of the character described, comprising in combination, a deck, a life saving buoy normally disposed on the deck, guys attached to the deck and connected with the buoy for holding it in upright position, means releasable from within the buoy to disconnect the guys, a launching davit and means controllable from within the buoy for suspending and lowering the buoy from the launching davit and means operable from within the buoy for releasing it from the suspending means.

2. A life saving equipment, comprising in combination, a deck, a life saving buoy normally disposed on the deck, guys attached to the deck and having ends projected through openings in the buoy, and locking pins releasably applied to said ends; said pins being releasable from within the buoy, a launching davit, a cable for launching the buoy connected with the davit and with the buoy through the medium of a bail; said bail having ends projected into the buoy through openings therein with locking keys through said ends releasable from within the buoy.

Signed at Seattle, Washington, this 10th day of December, 1928.
